CANOPIED BUILDING ENTRANCE

James E. Wheeler, 2256 Kent Blvd. NE.,
Grand Rapids, Mich.

Filed Mar. 20, 1959, Ser. No. 55,090

Term of patent 14 years

(Cl. D13—1)

Fig. 1 is a perspective view of a canopied building entrance embodying my design. The portion shown in broken lines is for illustrative purposes only.

Fig. 2 is a side plan view of my canopied building entrance.

I claim:

The ornamental design for a canopied building entrance, substantially as shown and described.
